COMBINED TOY WHISTLE AND FLASHLIGHT

Sidney Schwartz, New York, N. Y.

Application January 31, 1958, Serial No. 49,454

Term of patent 7 years

(Cl. D34—15)

Fig. 1 is a top plan view of a combined toy whistle and flashlight, showing my new design;

Fig. 2 is a side elevational view;

Fig. 3 is a front elevational view;

Fig. 4 is a rear elevational view and

Fig. 5 is a bottom plan view thereof.

I claim:

The ornamental design for a combined toy whistle and flashlight, as shown.
